UNITED STATES PATENT OFFICE

ROBERT STEWART, OF OZONE PARK, NEW YORK

WASH RAG

Application filed September 16, 1931. Serial No. 563,067.

My present invention in its broader aspects is concerned with the provision of a pad which may have a wide and varied field of usefulness. Such pads with slight modification may be made up as cleaning pads, wash cloths, powder puffs, etc., and regardless of the specific type of article in which the invention is embodied, certain characteristics of the pad itself prove peculiarly advantageous in use.

An object of the invention is to provide a pad capable of convenient manual application to a surface, to be treated. The pad in all instances is sufficiently soft to afford a substantial cushioning body material between the users hand and the surface to be operated on.

Another object is to provide a pad in which the padding material, that is the filler, may be formed of material which would ordinarily become matted or rotted or mouldy or otherwise rendered objectionable or unsanitary if wetted, and to so protect this material that the outside operating surface of the pad may be readily washed or scrubbed and thoroughly cleansed with soap and water without in any way wetting the padding material or in affecting the resilience thereof.

Another object is to provide a pad which will dry quickly when washed and which is not subject to permanent distortion regardless of the manner in which the pad may be manually or otherwise crumpled or crushed in use.

Another object is to provide a pad cover presenting an outer surface of any desired type of fabric and an entirely water-proof inner surface, the fabric and the water-proof material being preferably intimately bonded together so that they may be conveniently cut to size from large sheets of material and the composite covering material being so formed that a substantially water-proof seam may be formed by simply sewing the edges of two layers of the material together with a line of ordinary stitching.

Another object of the invention is to provide a wash cloth or face cloth in the form of a pad which will combine softness and substance of body with a tailored appearance

and with an outside surface which is of the conventional character commonly used for wash cloths and with the inherent ability to retain its shape under all conditions of use and to dry in a quick and sanitary fashion 55

In accordance with a preferred embodiment of the invention, the pad as typically embodied in a wash cloth, construction, includes a body of resilient water absorbent 60 padding material encased in a water-tight cover. The cover may consist of a laminated material with an outside fabric surface and an inside rubber surface or other water impervious surface intimately and permanently bonded to the fabric. The cover is substantially tailored and shaped to fit the pad within it and when the material constituting the cover is closed by a line of stitching, the mere act of tensioning the stitches seems to 65 draw the adjacent overlying edges of the cover lining together with sufficient firmness to preclude the admission of water to the padding material within the cover.

Contrary to prior types of padded face cloths in which water pervious covers have admitted both water and soap to a sponge or other absorbent padding medium the present device is highly sanitary in that only its outer surface ever becomes wet. Such surface is naturally quick drying and the danger of the cloths or pads becoming moldy or smelly due to the slow drying nature or the hygroscopic nature of the pad, is completely eliminated. At the same time all the advantages of the padded wash cloth are retained. It offers substantial bulk and softness and is pleasant to use. The resilient nature of the inner lamination of the cover material tends inherently to maintain the pad or padded wash cloth in its original tailored form.

Thus unlike an ordinary wash cloth, the device of the present invention after use cannot be carelessly tossed aside as a crumpled saturated ball but will tend to straighten itself out and facilitate quick drying and will be in a dry and sanitary condition when required for further use.

The advantages of this invention when the

pad is embodied in a powder puff, correspond generally to the advantages of using the pad as a wash cloth. Furthermore, in a powder puff constructed in accordance with the invention, the special cover prevents fine dust or grit from sifting through the cover to the padding material proper and permits soiled powder or the like, to be conveniently removed from the cover by washing.

10 The device is effective as a cleaning pad because it will protect the hands of the user from being bruised or injured by contact with the article to be cleaned even though substantial pressure is applied to the pad 15 during a cleaning operation. Obviously, other articles of manufacture might embody the structural features of the pad which constitutes the subject matter of the present invention and I therefore do not wish to limit 20 myself to its specific use as a wash cloth, powder puff or cleaning pad but intend the word "pad" to cover all generally analogous articles.

The invention may be more fully understood from the following description in connection with the accompanying drawing, wherein,

Fig. 1 is a perspective view illustrating a padded wash cloth embodying my invention;

20 Fig. 2 is an enlarged transverse sectional view taken on the line 2—2 of Fig. 1;

Fig. 3 is a perspective view of a section of a padding;

25 Fig. 4 is an exaggerated fragmentary perspective view of the composite cover fabric;

Fig. 5 is a sectional detail on the line 5—5 of Fig. 1;

30 Fig. 6 is a perspective sectional view showing a powder puff embodying the invention, and

Fig. 7 is a reduced perspective view of the powder puff of Fig. 6 showing the condition of the latter after it has been everted and 45 stuffed and before the puff has been completely closed.

Referring first to the padded wash cloth shown in Figs. 1 to 5 of the drawing, the padding material consists of a plurality of laminations of cotton batting 10 with cheese cloth 11 interposed between them and with the cheese cloth and batting sewed together by a plurality of lines of stitching 12 which may run diagonally or in any desired directions. The purpose of this stitching is to prevent the padding from slipping or crumpling between the cheese cloth laminations. It is in effect, a quilting stitch.

The cover for the pad consists of a composite rubber and fabric material formed in any well known manner, as for instance, by applying liquid, chemically treated rubber 13 to a fabric 14 (typically terry cloth) and calendering them together so that the fabric 65 becomes partially embedded in and inti-

mately bonded to the rubber which constitutes the lining of the fabric. Neither the manner of forming this composite cover material nor the cover material per se are my invention but any method of producing a corresponding cover or any generally similar cover however produced are within the spirit of the claims directed to my improved pad.

The cover may consist of a pair of similarly shaped cover sections or may consist of an elongated cover section as shown, folded back over the padding and having three edges sewed together by an overlocking stitch 15.

75 In practice, the edges of the cover which are sewed together are raw edges, the fabric of course, being kept from raveling by its bond with the rubber. When these edges are sewed together by a line of overlocking stitching, the opposed rubber faces are pressed together sufficiently firmly simply by the tension of the stitches (applied during the machine sewing operation) to prevent any ingress of water through the seam. Even when sewed with an ordinary machine stitch and without any lapping over, the cover is sealed with sufficient tightness so that the pad may be soaked in water for hours without any water penetrating to the padding material.

90 The inherent tendency of the complete cover fabric to restore itself to its normal flat condition is aided by the inherent resiliency of the padding material itself.

95 If desired, the edges of the padding material may be caught by the line of overlocked stitching to prevent the possibility of slippage of the padding material. For all ordinary purposes, however, if the padding material and cover are fairly carefully cut to size, there is no danger of the padding becoming displaced or matter or lumpy in the ordinary course of use.

100 An unusual characteristic of the wash cloth is the fact that the composite cover with its interior rubber surface is substantially self-restoring to its original shape after the cloth has been crumpled in use. Unlike the ordinary wash cloth which must be carefully unfolded and hung up to dry, a wash cloth constructed in accordance with the present invention is more or less inherently self-distraining so that quick dry is promoted, it being understood of course, that the only surface which is wet is the outer surface of the pad or cloth. The inherent tendency of the composite cover fabric to restore itself to its normal flat condition is aided by the inherent resiliency of the padding material itself.

110 115 120 125 130 The use of the handle strap 16 illustrated in the drawing is entirely optional. This strap, of any suitable material, overlies one face of the pad and has its ends secured by the line of stitching 15 which closes the cover. The purpose of the handle strap is

to permit the user to slip one hand under the strap and manipulate the cloth or pad without the necessity for gripping the latter with the fingers.

5 Figs. 6 and 7 show another typical embodiment of the invention. The pad in this instance, takes the form of a powder puff. Here similar padding material is used and the cover material is a composite sheet, preferably of velour 16 intimately bonded to a rubber lining 17. The cover may be sewed together in the customary manner, that is, by sewing it throughout approximately $\frac{1}{8}$ of its circumference, then evertit to conceal the line of stitching 18 and then closing the remaining gap 19 by hand or machine stitching after the padding material has been inserted.

Obviously, the particular shape of either 20 the wash cloth or the powder puff or any other pad constructed in accordance with the invention, may be infinitely varied to suit the requirements of the trade and various pads of ornamental conformation may be produced 25 in accordance with the invention.

When the invention is embodied in a powder puff, there is not only produced a washable puff but one in which there is no danger of grit or dust penetrating the cover 30 and entering the padding material proper. Inasmuch as the only surfaces where either dust or powder may collect is within the pile of the velour, it will be seen that by simply washing the pad in soap and water, it may 35 be thoroughly cleansed and after washing will be in a highly sanitary condition.

As in the case of the wash cloth, the use 40 of the rubberized or rubber faced fabric and resilient padding in the puff contributes materially to maintaining the original shape thereof under the usual vicissitudes of handling and of being transported in vanity cases or hand bags into which it may be casually stuffed.

45 It will thus be seen that there is herein described a device in which the several features of this invention are embodied, and which apparatus in its action attains the various objects of the invention and is well 50 suited to meet the requirements of practical use.

As many changes could be made in the above construction, and many apparently 55 widely different embodiments of this invention could be made without departing from the scope thereof, it is intended that all matter contained in the above description or shown in the accompanying drawing shall be interpreted as illustrative and not in a 60 limiting sense except as set forth in the claims.

Having thus described my invention what I claim as new and desire to secure by Letters Patent is:—

65 1. A washable, non-absorbent pad of the

character described, including a cover consisting of a fabric material intimately bonded to a rubber lining material, a padding of resilient material within the cover, the cover being so sewed together around the padding 70 that the ingress of water to the padding is prevented.

2. A washable, non-absorbent pad of the character described, including a cover consisting of a fabric material intimately bonded to a rubber lining material, a padding of resilient material within the cover, the cover being so sewed together around the padding 75 that the ingress of water to the padding is prevented, the padding including a plurality of laminations of cotton batting with interposed sheets of fabric sewed to the batting to prevent bunching thereof.

3. As a new article of manufacture, a padded wash cloth including a filler of resilient padding material, a water proof cover encasing said material and including an integrally bonded inner surface of rubber and an outer surface of fabric.

Signed at New York in the county of New 90 York and State of New York, this 10th day of September, A. D. 1931.

ROBERT STEWART.
